US00D660124S

(12) **United States Design Patent**
Mashburn et al.

(10) **Patent No.:** US D660,124 S
(45) **Date of Patent:** ** May 22, 2012

(54) **BLADE HOLDER**

(76) Inventors: **Ronald G. Mashburn**, Sherwood, AR
(US); **Larry D. Mount**, Harrison, AR
(US)

(**) Term: **14 Years**

(21) Appl. No.: **29/367,636**

(22) Filed: **Aug. 10, 2010**

(51) LOC (9) Cl. **08-03**

(52) U.S. Cl. **D8/99**

(58) **Field of Classification Search** D8/95-99,
D8/107; D22/118; 30/154-162, 329-331,
30/339

See application file for complete search history.

(57) **CLAIM**

The ornamental design for a blade holder, as shown and described.

DESCRIPTION

FIG. 1 depicts a perspective view of the invention.

FIG. 2 depicts a top plan view of the invention.

FIG. 3 depicts a bottom plan view of the invention.

FIG. 4 depicts a front elevation view of the invention.

FIG. 5 depicts a rear elevation view of the invention.

FIG. 6 depicts a left elevation view of the invention; and,

FIG. 7 depicts a right elevation view of the invention.
